(57) **CLAIM**

The ornamental design for a cap with two visors for providing neck protection as shown and described.

DESCRIPTION

FIG. 1 is an operational isometric view of a cap with two visors for providing neck protection showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof; and,

FIG. 7 is a bottom plan view thereof showing my design. The broken line outline of the partial human figure in FIG. 1 assists to illustrate how the claimed design may appear in a condition of use, but forms no part of the claimed design.
